DESCRIPTION

FIG. 1 is a top, front, left side perspective view of a collapsible bag. The broken lines depicting an outline of a hook represent environmental matter and form no part of the claimed design.

FIG. 2 is a front elevation view of a collapsible bag, the rear elevation view being a mirror image. FIG. 2 is a multi-sheet FIG., and each A-B portion forms a single complete figure. FIG. 3 is a rear elevation view of a collapsible bag. FIG. 3 is a multi-sheet figure, and each A-B portion forms a single complete figure.

FIG. 4 is a left side elevation view of a collapsible bag, the right side elevation view being a mirror image.

FIG. 5 is a top plan view of a collapsible bag.

FIG. 6 is a bottom plan view of a collapsible bag; and, FIG. 7 is a top, front, right side view of a collapsible bag in an alternate configuration.

The dominant features of my design reside in handles, a bottom portion, and a hinge to be used in combination with a collapsible bag.
